UNITED STATES PATENT OFFICE.

IVAN C. BELL, OF CAMERON, TEXAS, ASSIGNOR TO THE GUIERSON CORPORATION, OF DALLAS, TEXAS, A CORPORATION OF DELAWARE.

MULTIPLE-CUTTER-DISK BIT.

Application filed January 5, 1925. Serial No. 540.

This invention relates to new and useful improvements in multiple cutter disk bits.

The object of the invention is to produce a four-way cutter bit of the type set forth 5 in my copending applications Serial No. 716,970 and Serial No. 749,547.

An advantage of such an improvement is that smaller disks and a greater number can be used, whereby increased cutting and longer life results.

Another feature of the improvement is that less vibration being had crystallization is reduced to a minimum and smoother running with less power is obtained.

15 Further a bit of this type is selfcentering in all formations, possesses greater strength and requires less skill on the part of the driller.

20 A construction designed to carry out the invention will be hereinafter described together with other features of the invention.

The invention will be more readily understood from a reading of the following specification and by reference to the accompanying 25 drawings, in which an example of the invention is shown, and wherein:

Fig. 1 is an elevation of a bit constructed in accordance with my invention,

30 Fig. 2 is an underside view of the same, Fig. 3 is a cross-sectional view on the line 3—3 of Fig. 1,

Fig. 4 is a cross sectional view on the line 4—4 of Fig. 1,

35 Fig. 5 is a vertical sectional view of the bit,

Fig. 6 is an enlarged sectional view on the line 6—6 of Fig. 1, and

Fig. 7 is a plan view.

In the drawings the numeral 10 designates 40 a bit body or stock having a reduced tapered pin 11 or any other drill stem connection at its upper end. The pin is surrounded by an outwardly directed shoulder 12. The upper portion of the stock is cylindrical, although this is merely a preferred design. The stock is formed with a depending axial stud 13. The stock has four equally spaced channels 14 in its outer surface provided in their bottoms with dovetailed vertical key ways 15.

45 Standards 16 are formed to fit in the channels and have keys 17 engaging in the key ways 15. These standards have their upper ends shouldered and cut back flush with the 50 surface of the stock, but throughout the

greater portion of their length, extend radially from the stock. The upper ends of the standards abut the upper ends of the channels and key ways, which thus take the upward thrust. The standards are fastened by screws 18. It is to be understood that the manner of seating and fastening the standards in the stock may be carried out in various manners.

55 Each standard has its lower end extending below the stock and is provided with recesses 19 and 20 with a web therebetween and an outer web 22 flush with the outer surface of the standard. The stud 13 is four sided and has its sides parallel to the webs 21. The sides of the stud are cut back from keyways 15 (Fig. 5) so that a shoulder 23 overhangs each side of the stud, whereby the webs 21 are spaced from the sides of the stud.

60 An axle 24 is provided for each standard and each axle comprises a screw threaded head 25 engaged in the outer web 22 and a reduced shouldered end 26 engaging in a socket 27 in the stud. Each axle passes through the web 21. On each axle is mounted a cutting disk 28 in the recess 19. This disk is thickest at its hub portion, being reduced or inclined one side toward its outer edge which is bevelled in the opposite direction, so as to flare from the web 21.

65 The width of the recess 19 is considerably greater than the thickness of the disk. This permits the disk to play radially of the bit on the axle. The disk has a central aperture 29 larger in diameter than the axle, whereby 70 the disk may move radially of the axle and may deflect or tilt from its normal vertical plane while rotating, thus wobbling on its axle.

75 As before stated the bores of the disks are made larger than the diameters of the axles, so that instead of having merely a turning fit and the play usually present, the clearance or play between the journal of each disk and its axle is such as to initially give the disk 80 a very loose fit and a lateral or vertical movement or both, relative to the axle. This results in an amplified wobble, oscillation or shifting of the disk which is most prominent at its periphery and also causes the disk to 85 rotate freely. The disk thus becomes self-sharpening and this sharpening is enhanced by the shearing action of the edge of the disk, due to wobble, oscillation or shift. The amplified movement not only makes for sharp- 90

ening and the retaining of the circular edge, but causes faster cutting due to the shearing action.

In further explanation, it may be stated after numerous tests by actual drilling, that the disks traversing circuitous or sinuous paths rather than singular circular paths and being under the downward pressure of the superimposed drill stem, not only cover a greater transverse area in their travel by peripheral contact with the bottom of the hole, but have a very effective self-sharpening action, due to the wobble, the lead or offset of the disks from the transverse axis of the bit body and the weight placed upon the disks. It is obvious that such disks will tend to chip off the rock and shale and will cut faster by keeping a sharp edge.

By maintaining a sharp cutting edge, by traversing a greater path and by moving transversely of its cutting arc, the disks cut faster. The advantage of a continuous drilling bit which goes through hard as well as soft formations; whereas it has been necessary heretofore to come out of the hole and change bits, is of greater advantage as will be appreciated by the driller. The offsetting of the axles with relation to the transverse axis of the bit is very important as this gives the disks a drag and adds to their cutting action. The central disks are also very effective in cutting out the core.

Between the web 21 of each standard and the stud 13, disks 30 and 31, respectively, are mounted on each axle. The disk 30 has a central aperture 30' and is otherwise the same as the disk 28, except that it is smaller in diameter. Each disk 31 is made flat on both sides and of constant thickness, but this is subject to variation. The stud has a round boss 32 surrounding each socket 27 which acts to keep the disks 31 from rubbing the sides of the studs.

The thickened hub and inclined side of the disk 30 spaces the surfaces apart. The disk 31 has an enlarged central aperture 31'. The disks 30 and 31 have ample play along the axle between the web and stud. By mounting the disks 30 and 31 as described they are disposed close to the center of the bit and thus cut within a shorter radius than if they were separated by a support therebetween.

A well 33 is bored axially in the pin 11 and stock 10. Water ducts 34 are counter-bored from the bottom of the well through the stock (Fig. 5) and standards 16 so as to discharge into the recesses 19 and 20 over the disks. It will be seen that the disks are copiously supplied with water or slush and are adequately washed. When the disks, axles or standards wear out they may be readily replaced by removing the screws 18 and removing the axles 24.

The disks successively increasing in di-

ameter outwardly of the bit will cause a slight crown on the bottom of the hole, thus centering the bit and making a straight hole.

Various changes in the size and shape of the different parts, as well as modifications and alterations may be made within the scope of the appended claims.

What I claim, is:

1. In a multiple cutter disk bit, a bit body, axles mounted at substantially right angles to each other and having their inner ends supported by the body at the lower end thereof, cutter disks loosely mounted on said axles and movable laterally thereon, and removable supports for the outer ends of all the axles attached to the body.

2. In a multiple cutter disk bit, a bit body, axles mounted at angles to each other and having their inner ends supported by the body, cutter disks loosely mounted on said axles and movable laterally and radially in a vertical plane, and removable supports for the outer ends of the axles attached to the body.

3. In a multiple cutter disk bit, a bit body, a plurality of cutter disks mounted at right angles to each other and being loose upon their journals so as to wobble when the bit is rotated, and removable standards seated in the body for confining said disks and for taking the wear as the bit is rotated.

4. In a multiple cutter disk bit, a bit body, a plurality of cutter disks mounted at angles to each other and being loose upon their journals so as to wobble when the bit is rotated, and removable standards seated in the body for confining said disks and for taking the wear as the bit is rotated, said standards projecting outwardly from the bit body.

5. In a multiple cutter disk bit, a bit body, removable wear members on the sides of the body at an angle to each other, transverse axles carried by the body and the members, and a plurality of cutter disks mounted to move longitudinally as well as vertically of said axles between said wear members and the body.

6. In a multiple cutter disk bit, a stock having a drill connection at its upper end, a stud depending from the bottom of the stock, standards mounted at an angle to each other on the stock, axles carried by the stud and standards, and wobbling disks mounted on the axles.

7. In a multiple cutter disk bit, a stock having a drill connection at its upper end, a stud depending from the bottom of the stock, standards mounted at an angle to each other on the stock, axles carried by the stud and standards, webs supporting the axles between the stud and standards, and disks having each a hub thickness less than the spaces between the axle supports, whereby said disks are free to move longitudinally.

of the axles, said disks being loose upon their axles so as to wobble.

8. In a multiple cutter disk bit, a stock having a drill connection at its upper end, 5 a stud depending from the bottom of the stock, standards mounted at an angle to each other on the stock, axles carried by the stud and standards, webs supporting the axles between the stud and standards, disks having 10 each a hub thickness less than the spaces between the axle supports, whereby said disks are free to move longitudinally of the axles, said disks being loose upon their axles so as to wobble, and ducts in the stock for supplying liquid to each disk.

9. In a multiple cutter disk bit, a stock having seats at substantially right angles to each other, a stud depending from the center of the stock, standards engaging in said 20 seats and projecting outwardly from the stock, axles having their inner ends supported in the stud and their outer ends engaged in the standards, means for holding the standards in the stock, and a plurality 25 of disks loosely mounted on each axle so as to wobble when the bit is rotated.

10. In a multiple cutter disk bit, a stock having seats at substantially right angles to each other, a stud depending from the center of the stock, standards engaging in said 30 seats and projecting outwardly from the stock, axles having their inner ends supported in the stud and their outer ends engaged in the standards, means for holding the standards in the stock, each standard having a web at its lower end supporting 35 axles, the standards having recesses at the webs, and a plurality of cutter disks loosely mounted on each axle so as to wobble, some of the disks being separated by the web.

11. In a multiple cutter disk bit, a bit body having a central depending stud, a plurality of axles disposed at an angle to each other and in substantially the same horizontal plane with their inner ends supported by said stud, cutter disks loosely mounted on said axles and movable while revolving out of their normal plane, and supports carried by the body for the outer ends of the axles.

In testimony whereof I affix my signature.
IVAN C. BELL.
